UNITED STATES PATENT OFFICE.

EDWIN L. HARMON, OF GROTON, NEW YORK, ASSIGNOR TO CORONA TYPEWRITER COMPANY, INC., OF GROTON, NEW YORK, A CORPORATION OF NEW YORK.

TYPEWRITING MACHINE.

1,404,201.

Specification of Letters Patent. Patented Jan. 24, 1922.

Application filed July 15, 1919. Serial No. 311,027.

To all whom it may concern:

Be it known that I, EDWIN L. HARMON, a citizen of the United States of America, and a resident of Groton, county of Tompkins, and State of New York, have invented 5 certain new and useful Improvements in Typewriting Machines, of which the following is a full and clear specification.

The object of this invention is to provide simple means whereby a full operation 10 of the ribbon-vibrator is assured before the type strikes the ribbon, so as to thereby prevent the type beating the ribbon to the platen. It has been the fault of many ribbon-vibrating mechanisms that through 15 sluggishness or lost-motion the type will, when the machine is operated rapidly, get to the platen before the ribbon-vibrator has raised the ribbon entirely to the proper 20 color, with the result that the type strikes upon the dividing line between the two colors and thus causes the letters to have a tinge of black along their upper ends when 25 the mechanism is adjusted for printing red. It is the purpose of the present invention to provide against this parti-colored printing.

In the drawings—

Fig. 1 is a vertical sectional view of a typewriting machine showing my invention 30 applied thereto;

Fig. 2 is a similar view showing the parts in the position they assume when the type has struck the ribbon;

Fig. 3 is a detail perspective view of the 35 universal-bar and the ribbon-vibrator-operating bail.

I have illustrated my invention as applied to a machine of the Corona type, in which is employed an upright bail consisting 40 of upright arms 5 pivotally mounted at 6 to the frame if used in a segment-shift machine, as shown. The top-bar 7 of the bail is provided with a rearwardly-extending tappet 8 which is adapted to operate the 45 usual escapement (not shown) and with an upwardly-extending lug 9 adapted to operate the ribbon-vibrator, designated generally by the numeral 10, the type of vibrator shown being similar to that covered by 50 Petermann Patent No. 1,121,040, dated December 15, 1915, wherein the rearward movement of the top-bar of the bail causes the vibrator to lift the ribbon to the desired height for printing one color or the other.

In my present invention, each of the up-

right arms 5 of the bail depends below the pivotal point 6 and the rear edge of this pendent member is formed into a cam surface 11, at the lower end of which is provided a rearwardly-extending lug 12. A universal 60 bar 13 of the usual construction is pivoted at 14 to the frame of the machine, and the side arms 15 of this universal bar are extended rearwardly to form levers 16 whose rear ends are bent slightly inwardly to 65 form ears 17 which are so located as to lie near or rest upon the upper faces of the lugs 12 when the parts are at rest, as shown in full lines in Fig. 1.

When the universal bar is depressed by 70 one of the key-levers in the usual manner, as shown in dotted lines in Fig. 1 and in full lines in Fig. 2, the lug 17 impinges against the cam 11 and thus pulls the pendent ends of the bail arms forwardly, thereby swing- 75 ing the top bar 7 of the bail rearwardly to cause an action of the escapement as well as the ribbon-vibrator. The cam 11 is so shaped that the ribbon-vibrator receives full operation before the type reaches the platen, 80 this being shown in dotted lines in Fig. 1, in which the lug 17 is shown as having reached the end of the active part of the cam face, at which point the movement of the bail arms ceases, a complete operation of the vi- 85 brator having been accomplished, as stated. During the remaining part of the move- ment of the type-bar action, that is, during the time the parts move from the dotted-line position shown in Fig. 1 to the full-line po- 90 sition shown in Fig. 2, the movement of the lug 17 is an idle one, except that it serves to hold the bail and connected vibrator in writing position until the type-bar completes its movement. When the key is released and the type action and universal bar are re- 95 stored to normal by gravity and the usual spring (not shown), the lugs 17 fall to a position at rest on the lugs 12, as shown in full lines in Fig. 1.

It will be observed that I provide a very simple direct-acting device for translating the movement of the universal bar into a complete operation of the ribbon-vibrator, irrespective of the speed of operation of the 105 machine, thereby insuring against parti-colored or smeared writing.

It will be understood that the invention may be embodied in various forms of type- 110 writing machines,

It will be observed that the connection between the lugs 17 and the bail is such that the latter part of the upward movement of the lugs is an idle or excess movement, 5 the cam action having ceased by reason of the fact that the bail has been shifted far enough to bring the vibrator to printing position. This idle or excess movement of the lugs 17 is necessary, obviously, by reason 10 of the fact that a further movement of the universal bar is needed in order to permit the type-bar action to have a complete operation. I contemplate so shaping the cam surface 11 that the vibrator-operating bail 15 will have been caused to make its complete stroke by the time the type-bar has traveled about two-thirds of the distance from the type-bar rest to the platen, as that percentage of the distance will be ample to compensate for any lost-motion due to loose 20 pivots or flexibility of the parts.

The nature and scope of the invention having been thus indicated and its preferred embodiment having been specifically described, what is claimed as new is:

1. In a typewriting machine, the combination of an upstanding rocking frame for operating a ribbon-vibrator, means pivotally supporting said frame to rock fore and aft of the machine, a universal bar, levers extending fore and aft of the machine supporting the universal bar, means pivotally supporting said levers intermediate the ends thereof to rock up and down, and direct excess-motion connections between the rear ends of said levers and said frame for imparting a full movement in one direction to the frame during the initial portion of the movement of the universal bar in one 30 direction and holding said frame stationary during the final portion of said movement of the universal bar and the initial portion of the return movement of the bar.

2. In a typewriting machine, the combination of an upstanding inverted U-shaped bail for actuating an escapement and ribbon vibrator, means pivotally supporting the depending side members of the bail to swing fore and aft of the machine, a universal bar, 40 a pair of levers supporting the universal bar at their forward ends, means pivotally supporting the levers intermediate their ends to rock up and down, direct cam connections between the rear ends of said levers and the side members of the bail for rocking the bail rearwardly when the universal bar is moved downward, and key-operated levers for operating type-bars adapted to move the universal bar downward when keys are 50 depressed.

3. In a typewriting machine, the combination of an upstanding escapement and ribbon-vibrator actuating frame, means for pivotally supporting the frame intermediate 60 its upper and lower ends to rock about an

axis extending transversely of the machine, a universal bar frame extending fore and aft of the machine, means pivotally supporting said universal bar frame intermediate its ends to rock about an axis extending transversely of the machine, 70 said universal bar frame slidably engaging the upstanding frame below the pivotal axis of the frame for rocking the upstanding frame fore and aft of the machine.

4. In a typewriting machine, the combination of an upstanding escapement and ribbon-vibrator actuating frame, means for pivotally supporting the frame intermediate its upper and lower ends to rock about an axis 80 extending transversely of the machine, a universal bar frame extending fore and aft of the machine, means pivotally supporting said universal bar frame intermediate its ends to rock about an axis 85 extending transversely of the machine, said universal bar frame having a cam connection at the rear of its pivotal axis with the lower portion of the upstanding frame for moving the upper portion of the frame 90 rearwardly during the initial portion of the downward movement of the forward part of the universal bar frame and holding the same stationary until the final portion of the return movement of the universal 95 bar frame, and key levers adapted to engage and move the forward part of the universal bar frame downward when the keys are depressed.

5. In a typewriting machine, the combination of an upstanding escapement and ribbon-vibrator actuating frame, means for pivotally supporting the frame intermediate its upper and lower ends to rock about an axis extending transversely of the machine, 100 a universal bar frame extending fore and aft of the machine, means pivotally supporting said universal bar frame intermediate its ends to rock about an axis extending transversely of the machine, key levers 110 adapted to engage and move the forward part of the universal bar frame downward when the keys are depressed, and means directly connecting the universal bar frame at the rear of its pivotal axis with the upstanding frame below the pivotal axis of the latter frame for rocking the upstanding frame fore and aft of the machine.

6. In a typewriting machine, a bail for operating the ribbon-vibrator, said bail having a pair of depending upright arms pivoted at their lower ends, said lower ends of the arms being provided with pendent cams facing rearwardly, and a universal bar having a pair of arms extending rearwardly and provided with lugs adapted to impinge against said cams when the universal bar is operated and thus swing the upper end of the bail rearwardly during the initial part of the movement of the universal bar, the 120 125 130

5 cams being so shaped as to permit a further idle movement of the lugs after the bail has been shifted to operative position to thereby permit a completion of the movement of the type-bar action.

7. In a typewriting machine, the combination of an upstanding ribbon-vibrator actuating member, means pivotally supporting said member to swing fore and aft 10 of the machine about a horizontal axis, a lever supported intermediate its ends on a horizontal pivot and extending fore and aft of the machine, a universal bar connected with said lever at one side of its pivot, and 15 means forming a cam connection between said lever and the upstanding member at the opposite side of the pivot of the lever for shifting the upstanding member, said cam connection having a dwell therein for 20 holding the upstanding member temporarily in its shifted position.

8. In a typewriting machine, the combination of type bars, key levers operatively connected to actuate the type bars, a swinging 25 member movable fore and aft of the machine for operating a ribbon vibrator, a cam carried by said member having active and dwell surfaces, a swinging universal bar operable by the key levers, an arm 30 rigidly connected with said universal bar adapted to ride over the active surface of said cam before a type bar reaches the printing point and ride over the dwell surface of said cam during the final movement of 35 the type bar to the printing point.

9. In a typewriting machine, the combination of a ribbon vibrator, an upstanding rocking frame extending transversely of the machine, a pair of cams carried by said 40 frame at opposite sides of the machine, a universal bar, a pair of arms rigidly connected with the universal bar at one end and having a sliding contact with said cams at their other ends, and means for supporting 45 said bar and arms to rock about an axis extending transversely of the machine.

10. In a typewriting machine, the combination of an upstanding pivotally supported bail for operating a ribbon vibrator, 50 cams rigidly held to the side arms of said bail, a universal bar extending transversely of the machine, and a pair of rock arms movable with said bar extending fore and aft of the machine and cooperating with said 55 cams to swing the bail fore and aft of the machine.

11. In a typewriting machine, the combination of type bars, key levers operatively connected to actuate the type bars, an up- 60 standing pivotally supported bail for operating a ribbon vibrator, cams rigidly held to the side arms of the bail having active and dwell surfaces, a universal bar extending transversely of the machine and oper- 65 able by the key levers, and a pair of rock

arms movable with said bar extending fore and aft of the machine and having end portions cooperating with said cams to swing the bail fore and aft of the machine, said end portions of the rock arms being adapted to 70 ride over the active surfaces of the cams during the initial movement of a type bar toward the printing point and ride over the dwell surfaces of the cams during the final movement of the type bar to the printing 75 point.

12. In a typewriting machine, the combination of type bars, key levers operatively connected to actuate the type bars, an upstanding bail having cam surfaces formed 80 on the rear edges of its side arms, means for pivotally supporting the side arms of the bail above said cam surfaces, a universal bar underlying the key levers and operable thereby, levers supporting said universal bar 85 at their forward ends and provided with lateral extensions at their rear ends engaging the cam surfaces on the bail, means for pivotally supporting said levers intermediate their ends, and ribbon vibrating means oper- 90 able by said bail.

13. In a typewriting machine, the combination of type bars, key levers operatively connected to actuate the type bars, an upstanding bail having cam surfaces formed 95 on the rear edges of its side arms, means for pivotally supporting the side arms of the bail above said cam surfaces, a universal bar underlying the key levers and operable thereby, levers supporting said universal bar 100 at their forward ends and provided with lateral extensions at their rear ends engaging the cam surfaces on the bail, means for pivotally supporting said levers intermediate their ends, ribbon vibrating means operable 105 by said bail, and an escapement operating tappet mounted on the bail, the lateral extensions on the levers cooperating with the cam surfaces on the bail arms to impart a full rearward movement to the bail before 110 the universal bar is fully depressed and before a type bar reaches the printing point and having a subsequent idle movement.

14. In a typewriting machine, the combination of an upstanding rocking frame for 115 actuating an escapement and a ribbon vibrator, type bars, key levers operatively connected to actuate the type bars and fulcrumed at their rear ends, a universal bar underlying the key levers and depressible 120 thereby, a pair of levers extending fore and aft of the machine supporting the universal bar at their forward ends, means for pivotally supporting said levers intermediate their ends, and means forming an up-and-down 125 sliding connection between the rear ends of said levers and the rocking frame for rocking the frame fore and aft of the machine.

15. In a typewriting machine, the combination of an upstanding rocking frame for 130

actuating an escapement and a ribbon vibrator, type bars, key levers operatively connected to actuate the type bars and fulcrumed at their rear ends, a universal bar underlying the key levers and depressible thereby, a pair of levers extending fore and aft of the machine supporting the universal bar at their forward ends, and means for

pivottally supporting said levers intermediate their ends, the rear ends of said levers 10 directly and loosely engaging a part of said frame and adapted to rock the frame fore and aft of the machine.

This specification signed this 10th day of July, A. D. 1919.

EDWIN L. HARMON.
